RHEOSTAT AND THE LIKE

Filed July 31, 1922

Fig. 4.

Inventor
Erwin R. Stockle

UNITED STATES PATENT OFFICE.

ERWIN R. STOEKLE, OF MILWAUKEE, WISCONSIN.

RHEOSTAT AND THE LIKE.

Application filed July 31, 1922. Serial No. 578,823.

To all whom it may concern:

Be it known that I, ERWIN R. STOEKLE, a citizen of the United States, residing at Milwaukee, in the county of Milwaukee and 5 State of Wisconsin, have invented new and useful Improvements in Rheostats and the like, of which the following is a full, clear, concise, and exact description, reference being had to the accompanying drawings, 10 forming a part of this specification.

This invention relates to improvements in the construction of regulable rheostats of the type especially adapted to the control and regulation of small currents such as occur in radio apparatus and instrument regulation.

An object is to provide a rheostat structure that will hold a helically wound resistor element firmly in place in a groove at 20 the circumference of a cylindrical structure.

Another object is to provide a structure in which the groove for retaining the resistor element is formed by the assembly of moulded or punched circular disks.

25 Another object is to provide an improved rheostat structure in which the resistor is retained between circumferentially grooved metal disks electrically insulated therefrom, whereby effective cooling of the resistor is obtained by thermal conduction to and 30 radiation from the metal disks.

Another object is to provide an improved rheostat in which both coarse and fine adjustment of the resistance may be obtained 35 by means of a single operating knob, the device for accomplishing fine adjustment being a simple attachment to the plain rheostat.

Another object of this invention is to provide 40 an improved rheostat in which both fine and coarse adjustments of the resistance may be independently accomplished and independently indicated at the operating knobs or handles.

45 The novel features and improved structure of this rheostat are made clear by the following description and the drawings of Figs. 1 to 4.

Figure 1 shows in cross section a preferred 50 form of the simple rheostat. Fig. 1^A shows a somewhat simplified disk assembly and method of holding the resistor in place.

Figure 2 is a rear view of the simple

rheostat showing the contact arm and binding posts in relation to the resistor. 55

Figure 2^A is a perspective view of the plain rheostat of Figs. 1 and 2 with a simple attachment for accomplishing fine adjustment of the resistance, by means of a single knob. 60

Figure 3 is a perspective view of the rheostat with simple modifications to accomplish fine adjustment of the resistance, and to independently indicate the fine and coarse 65 adjustments.

Figure 4 is a cross section of the rheostat shown in Fig. 3.

Referring to the Fig. 1 the helically wound resistor 1 is shown retained in a groove formed by the superposition of the disks 2, 3, 4, 5 and 6. The outside disks 2 and 6 are preferably of sheet metal with their edges turned slightly inward. The disks 3 and 5 are of insulating material such as paper or thin fibre, and the disk 4 is likewise of insulating material such as fibre. 70

The assembly of these disks with the resistor is accomplished as follows: The disks 4, 5 and 6 are assembled over the hollow rivet or grommet 7, and the resistor 1 which may be in the form of a long helical spring, 75 is stretched around the disk 4. The disks 2 and 3 are then superposed and the whole firmly compressed by turning over the edges of the grommet 7. 80

Figure 1^A shows another method of assembling the resistor between the disks and eliminates the center disk 4. In this construction it is necessary to press circular grooves 23 and 24 near the edges of the 90 disks 61 and 62. These disks are held in compression by the bushing 25, and the pressure exerted by the disks upon the helical resistor 26 serves to hold the turns of the resistor in circumferential and radial alignment. Thin insulating discs 63 and 64 insulate the resistor 26 from discs 61 and 62. 95

Referring again to Fig. 1 the shaft 8 extends rotatably through the grommet 7 and the panel 9 upon which the rheostat is mounted. The front end of this shaft has fastened to it the pointer 10 and the operating knob 11. The contact arm 12 is fastened as shown to the collar 13 which is adjustably fixed to shaft 8 by means of a set 100 screw 14. 105

The binding post 15 is fastened to the insulating disk 4 by means of the screw 17 and is electrically connected to one end of the resistor element. The binding post 18 (Fig. 2) is fastened to the metal disk 2 as well as the insulating disk 4 by means of the screw 19. A spring washer 20 serves to make good electrical connection between the disk 2 and the contact arm 12.

10 The current therefore enters at binding post 15, passes through the resistor to the point where the latter is in contact with the arm 12, thence through the spring washer 20 to the metal disk 2 and binding post 18.

15 The holes 21 and 22 are for the mounting screws, that fasten the rheostat to the panel.

Figure 2^A shows the rheostat with a simple attachment for obtaining very fine and gradual adjustment of the resistance. In 20 this figure an insulating sector 27 is fastened to the hub 28 which is rotatable on the shaft 29. This sector carries the contact arm 30 which bears on the resistor 65, and also carries a slide wire 31 one end of 25 which is fastened to the pin 32, and the other end of which is electrically connected to the arm 30. The contact arm 33 which is fixed to the rotatable shaft 29 bears upon the slide wire as shown.

30 The current enters at the binding post 34, passes through the resistor 65 to the contact arm 30, thence through the slide wire 31 to the contact arm 33. From this contact arm the current passes through the shaft 35 29 and the metal disks 36, to the binding post 35.

It is therefore apparent that a variable portion of the main resistor and of the slide wire are electrically in series so that a rotation of the knob 37 which is fastened to the shaft 29 will first vary the slide wire resistance in infinitesimal steps. When the contact arm 33 strikes the pin 32 on the contact arm 30, a further rotation of the 45 knob 37 will move the contact arm 30 on the main resistor and thus vary the resistance in steps equal to the resistance of any one turn of the main resistor.

In order to obtain infinitesimal variations 50 of the resistance at any value thereof, it is only necessary to have the total resistance in the slide wire 31 equal to or greater than the resistance of one turn of the main resistor.

55 It is thus apparent that infinitesimal variations of the resistance can be accomplished by the use of only a single operating knob.

It is obviously feasible to fasten the sector 60 27 to a tubular shaft extending through the rheostat and carrying a pointer at its exterior end, whereby the position of the contact shoe 30 upon the main resistor can be indicated at the front of the mounting panel.

65 Figures 3 and 4 show the rheostat with

attachments for obtaining very fine and gradual variations of the current by means of two operating knobs. The main resistor structure in these figures is the same as that shown in Figs. 1, 2 and 2^A.

70 Referring to the Fig. 4 a tubular shaft 38 extending rotatably through the mounting panel 59, and the grommet 58 has fastened to it by means of the collar 39 and set screw 40 an insulating disk 41, in the edge of which is cut a circumferential groove 75 retaining a slide wire 42. The contact arm 43 bears upon this slide wire and is fastened to the shaft 44 by means of a collar 45 and set screw 46. The shaft 44 extends rotatably through the tubular shaft 38 and its operating knob 47, and at its exterior end has fastened to it the operating knob 48.

80 The contact shoe 49 is fastened to the disk 41 and electrically connected to one end of the slide wire 42, the other end of the slide wire 42 is fastened to the insulating disk 85 by means of a pin 50.

85 Referring to Fig. 3 the current enters at the binding post 51, passes through the resistor to the contact shoe 49, thence through the slide wire 42 to the contact shoe 43. From 90 43 the current passes through the shafts 44 and 38 and the spring washer 52 to the metal disk 57 and the binding post 95 53. The spring 54 serves to hold the knob 48 against the knob 47 and also to make better contact between the hub 45 and the shaft 38.

95 It is apparent from the above description 100 and from the Fig. 3 that a movement of the contact 49 towards the binding post 51 decreases the resistance in steps equal to the resistance of one turn of the main resistor. It is further apparent that the movement of 105 the contact arm 43 towards 49 decreases the resistance in infinitesimal steps thus allowing of very fine and gradual adjustment of the resistance between the binding posts 51 and 53.

110 Referring again to the Fig. 4, the pointer 55 is threaded to the shaft 38 and serves to indicate in conjunction with a scale marked on the panel 59, the position of the contact shoe 49 upon the resistor 60. The pointer 56 is screwed on to the shaft 44 and serves to indicate in conjunction with a scale 115 on the knob 47 the position of the contact shoe 43 upon the slide wire 42. It is therefore possible to independently and accurately indicate by this arrangement, the magnitude of the resistance in the main resistor and in the slide wire.

120 What I claim is new and desire to secure by Letters Patent is:

1. A rheostat comprising a helically wound resistor whose axis lies in a circumferential groove formed by the co-axial superposition of a plurality of circular disks.

125 2. A regulable rheostat comprising a heli-

130

cally wound resistor whose turns are axially retained in a groove formed by the co-axial superposition of a plurality of circular disks; a contact arm bearing on the turns 5 of said resistor and fastened to a shaft rotatably extending through a central tubular rivet, said rivet holding said disks in compression, and exerting a pressure upon the resistor, whereby its turns are held in lateral and circumferential alignment in said groove.

3. A rheostat comprising a resistor axially retained in a circumferential groove formed by the co-axial superposition of two metal 15 disks near whose edges are pressed circumferential grooves, means for insulating the turns of said resistor from said metal disks, and means for compressing said disks whereby the turns of said resistor shall be firmly 20 held in said groove.

4. A rheostat comprising a resistor axially retained in a circumferential groove formed by the co-axial superposition of two metal disks near whose edges are pressed circumferential grooves, means for insulating the turns of said resistor from said metal disks, and means for compressing said disks whereby the turns of said resistor shall be firmly held in said groove, said resistor having its 30 outer edge exposed for the purpose of making contact with a contact shoe.

5. A rheostat comprising a helically wound resistor axially retained in a circumferential groove formed by the co-axial superposition 35 of a plurality of disks; namely, two outside metal disks with their edges turned over a portion of the outer part of said resistor; thin disks of paper or the like for insulating said resistor from said metal disks; a central insulating disk of smaller diameter than said 40 outside disks for holding said resistor in axial alignment with respect to said disks, and for supporting two binding posts; a tubular rivet for holding said disks in compression, and through which extends a rotatable shaft carrying a contact arm which 45 makes contact with the turns of said resistor.

6. A rheostat comprising a helically wound resistor axially retained in a circumferential groove formed by the co-axial superposition 50 of a plurality of disks, the two outside disks being of metal, said metal disks being electrically connected to a rotatable contact arm bearing on the turns of said resistor, and to a binding post; a second 55 binding post insulated from said metal disks and electrically connected to one end of the wire of said resistor.

7. A regulable rheostat comprising a circularly disposed main resistor, a co-axially rotatable insulating member, said member carrying a contact arm bearing on the turns 60 of said resistor; a slide wire mounted on said member and having one of its ends electri-

cally connected to said contact arm; a second 65 rotatable contact arm bearing upon said slide wire, and movable thereon between stops at the ends of said slide wire, said stops serving as a means of rotating said sector and its associated contact arm by the rotation of 70 said second contact arm.

8. A rheostat comprising a helically wound resistor axially retained in a circumferential groove formed by the co-axial superposition of a plurality of circular 75 disks; a rotatable tubular shaft extending co-axially through said disks and carrying a circular insulating disk on the edge of which is a circumferential groove retaining a slide wire; a contact arm fixed to said insulating disk and electrically connected to one end of said slide wire, said contact arm bearing on the turns of said resistor; a second contact arm bearing on said slide wire, and fastened to a shaft extending through 80 said first mentioned tubular shaft.

9. A rheostat comprising a resistor axially retained in a circumferential groove formed by the co-axial superposition of a plurality of circular disks, a co-axially rotatable insulating disk carrying a contact arm bearing on the turns of said resistor; a slide wire laid in a circumferential groove in said disk, one end being connected to the said contact arm, the other end being suitably secured to 95 said disk; a second contact arm bearing on said slide wire and mounted on a rotatable shaft, through which it is electrically connected to two outside metallic disks enclosing the main resistor; two binding posts, one of 100 which is electrically connected to said metal disks the other of which is insulated therefrom and connected to one end of the wire of said resistor.

10. A rheostat comprising a circularly disposed resistor, an insulating disk carrying a contact arm bearing on the turns of said resistor and fixed to a rotatable tubular shaft the exterior end of which has fastened to it an operating knob and a pointer for indicating 105 the position of said contact arm with respect to said resistor; a slide wire laid in a circumferential groove in the said insulating disk, one end being connected to the said contact arm the other end being suitably secured to the disk; a second contact arm bearing on said slide wire and mounted on a rotatable shaft extending through said tubular shaft and its operating knob; an operating 110 knob and a pointer fastened to said shaft for the purpose of indicating upon a scale marked upon said first mentioned knob the position of said second contact arm upon said slide wire.

In witness whereof I have hereunto subscribed my name.

ERWIN R. STOEKLE.
